WAVE SETTER

Abraham Goodman, Brooklyn, N. Y., assignor to
Delamere Company, Inc., a corporation of
Delaware

Application July 18, 1934, Serial No. 735,804

1 Claim. (Cl. 132—31)

This invention relates to improvements in a wave setter, and has for its object particularly to provide means whereby a wave of hair may be firmly pressed between the opposed jaws of the device throughout their lengths and maintained under pressure until the wave is set.

Other objects and advantages of the invention will appear from the following description thereof, reference being had to the accompanying drawing, in which:

Figure 1 is a bottom plan view of a wave setter embodying the invention;

Fig. 2 is a side elevation thereof;

Fig. 3 is an end view; and

Fig. 4 is a section on the line 4—4 of Fig. 2, showing the jaws in open position.

The device comprises two jaw members 10—10, of aluminum or other suitable material, disposed in opposition to each other with their flat faces 11—11 in contact with each other throughout their lengths when the jaws are in closed position, as best seen in Fig. 3. Each jaw has an outwardly flared lower end 12, which lower end is curved lengthwise to conform substantially to the general curvature of the head, and an upwardly extending finger 13.

The two jaws are connected together by a rod or pin 14 which extends lengthwise through openings 15 in the overlapping ears 16 at the ends of the finger pieces. A spring 17, coiled about the rod 14, serves normally to urge the two jaws together.

A series of teeth 18 are stamped out of the material of the portion 11 of each jaw, the teeth on the two jaws being staggered relatively to each other so that those carried on one jaw will come between those carried on the other when the jaws are closed. The teeth 18 are somewhat shorter than the width of the flange 12 and they extend inwardly at an angle such that when the jaws are closed, the teeth of one jaw will lie flat

against the flange of the opposite jaw, as shown in Fig. 3. The flanges 12 assist in giving the desired shape to the hair wave, and protect the teeth from being accidentally bent out of proper alignment.

In use, the hair is dampened and a wave is formed in the usual manner. The wave setter is then placed over the wave, with its jaws open as shown in Fig. 4. In this position, the opposed sets of teeth 18 engage downwardly in the hair and, as the jaws are closed, lift or raise the wave so that the crest comes in position between the opposed flat portions 11—11 of the two jaws. The pressure of the spring 17 causes the two opposed portions 11—11 to pinch the crest of the wave tightly, thus holding the wave under pressure until the hair is dried and the wave set. The openings 19, formed by stamping the teeth, serve to permit of circulation of air to facilitate drying the hair.

It will be understood by those skilled in the art that various modifications in the details of construction herein illustrated and described may be resorted to without departing from the spirit or scope of the invention.

What I claim is:

A wave setter comprising a pair of spring pressed arcuate-shaped jaws hinged together at their upper edges, said jaws having opposed flat portions that contact with each other throughout to press the hair tightly therebetween when the jaws are closed, and having diverging flange portions along their lower edges, each jaw carrying a set of spaced-apart teeth extending inwardly at an angle corresponding to the angle of the flange of the opposed jaw and lying flat against said flange when closed, the teeth of the two jaws being disposed in alternation with each other.

ABRAHAM GOODMAN.
